UNITED STATES PATENT OFFICE.

JOHN C. LONG, OF MECHANICSBURG, PENNSYLVANIA.

REGENERATIVE HOT-BLAST APPARATUS.

SPECIFICATION forming part of Letters Patent No. 248,483, dated October 18, 1881.

Application filed April 27, 1881. (No model.)

To all whom it may concern:

Be it known that I, JOHN C. LONG, a citizen of the United States, residing at Mechanicsburg, in the county of Cumberland and State 5 of Pennsylvania, have invented new and useful Improvements in Regenerative Hot-Blast Apparatus for Metallurgical Furnaces, of which the following is a specification.

My invention relates to certain improvements 10 in regenerative hot-blast apparatus for metallurgical furnaces; and the improvements consist in certain combinations and arrangements of parts, which will be first fully described, and then specifically pointed out in the claims.

15 Referring to the accompanying drawings, making part of this specification, and in which like letters of reference indicate corresponding parts, Figure 1 is a horizontal section through the perforated air cylinders and blocks 20 on line $z z$, Fig. 5. Fig. 2 is a horizontal section through the gas and air connections on line $y y$, Fig. 5. Fig. 3 is a horizontal section through the air cylinders and blocks on line 25 $z' z'$, Fig. 6, showing a modification of the dividing - pipe, distributing - main, connections, and combustion - chamber. Fig. 4 is a horizontal section of the same on line $y' y'$, Fig. 6. Fig. 5 is a vertical longitudinal section on line $x x$, Figs. 1 and 2, showing the hot and 30 cold gas and hot and cold air and chimney connections. Fig. 6 is a longitudinal section on line $x' x'$, Figs. 3 and 4, showing the hot and cold gas and hot and cold air and chimney connections, the same being a modification of the 35 parts shown in Fig. 5. Fig. 7 is a vertical section through the combustion-chamber on line $u u$, Figs. 1 and 2. Fig. 8 is a vertical section through the combustion-chamber on line $u' u'$, Figs. 3 and 4, showing a modification of the 40 dividing pipes, connections, mains, and combustion-chamber shown in Fig. 7. Fig. 9 is a vertical transverse section of the oven on line $v v$, Figs. 1, 2, 3, and 4. Figs. 10, 11, and 12 are 45 perspective views of portions of the walls, showing their construction, so as to provide against the effects of expansion and contraction. Fig. 13 is a longitudinal vertical section on line $y^2 y^2$ of Fig. 14 of an oven whose regenerator-flues are arranged in groups or sets, 50 showing the modified method of forming the horizontal distributing-flues. Fig. 14 is a horizontal section of the same on line $x^2 x^2$ of Fig. 13. Fig. 15 is a top or plan view of four com-

bined ovens and gas-heaters arranged in couples directly connected, having two gas-supply mains at hot or combustion chamber sides. Fig. 16 is a top or plan view of four combined ovens and gas-heaters arranged in couples and having a common gas-supply main connected to their several combustion-chambers. Fig. 60 55 Fig. 17 is a top or plan view of three combined ovens and gas-heaters arranged above a common gas-supply main. Fig. 18 is a top or plan view of three ordinary regenerative hot-blast ovens altered to my improved system without 65 adding a fourth ordinary oven or a combined oven and gas-heater.

The object of this invention is to provide a regenerative hot-blast oven which can be used either for heating the blast or for heating the 70 combustible gas burned in the apparatus, so that it may be substituted for either a special blast-oven or a special gas-heater, or both, in order to heat the combustible gas prior to its being burned in the apparatus, whereby a 75 more intense heat may be developed therein than when the apparatus is heated by the combustion of gas which has not been heated after leaving its source, and which is so arranged with suitable connections that it can 80 be used either for heating the blast or for heating the combustible gas by being heated for each object specially; or it can be used as a gas-heater without being specially heated therefor by making available the large quantity of heat 85 yet in the oven when used to heat the blast after it has lost that portion of its heat which is effective in heating the blast to the required 90 temperature, and which combined blast-oven and gas-heater may be substituted for either the special gas-heaters or blast-ovens, or for both, as aforesaid, so that when used as a gas-heater it can, in case of failure or repair of the 95 blast-ovens, be used for heating the blast, thus furnishing a duplicate set of blast-ovens without increasing the cost of the plant, and at the same time avoiding the danger incident to a failure of the hot blast by the giving out of the special blast-ovens; and in addition thereto the object is to furnish a means of altering 100 the regenerative hot-blast apparatus now in use to my improved system, either by adding thereto one or more combined blast-ovens and gas-heaters directly connected thereto, so as to 105 form couples, each consisting of an oven used as a gas-heater and an oven used as a blast-

oven, as hereinafter described, or all may be connected to a common hot-gas main, as in Fig. 16, and in both cases adding to the other ovens the necessary hot and cold gas and air connections, so that any or all may be used as blast-ovens or gas-heaters, as desired; or a plant consisting of four blast-ovens may be altered to my system where the ovens are arranged along a common cold-gas-supply main having no other branches by putting in the main a valve between the ovens and blast-furnace or other source of gas supply, and then using the portion thus cut off as a hot-gas main; or, in case each pair of ovens has a common gas-supply main without other branches, then by cutting it off as above described a hot-gas main is formed leading from one oven to the other, and the pair is worked as a couple. In both cases the necessary additional hot and cold gas and air connections are made so that any oven may be used as a gas-heater or blast-oven, as desired.

In the case of a plant consisting of three ovens it may, owing to the fact that the combustible gas necessary to heat the apparatus has a much smaller volume and less velocity and greater heat-absorbing power than the blast, while the specific heat is about the same in both cases, be altered to my improved system without increasing the number of ovens, by altering them into combined blast-ovens and gas-heaters by adding to the ovens the necessary cold-gas main and connections at the cool end, in order to supply the gas to be heated, and at the hot end a hot-gas main connecting all of the ovens; or, in case the ovens have a common gas-supply main, then, by cutting it off by a valve between the ovens and blast-furnace or other source of gas-supply, a hot-gas main is formed, using the ordinary gas-connections with the ovens for the passage of the heated gas. If it is desired to burn the heated gas with hot air, then the necessary connections must be made as hereinafter described; but if cold air is used for combustion, then the ordinary air-connections can be used.

A plant of three blast-ovens may also be altered by adding one of the combined ovens and gas-heaters and the necessary blast and gas and air connections to the other ovens and cutting off the gas-supply main, as above described.

The object is also to provide a means of heating a mixed blast of air and vapor, and at the same time furnish pure highly-heated atmospheric air for combustion in the ovens and gas-heaters; also, to provide for expansion and contraction and for the equal heating of the oven and equal distribution of the gas or blast to be heated.

In this specification, when speaking of "cold" or "cool" gas, I mean gas at the temperature it has after leaving the blast-furnace or other source of supply less the temperature lost in transmission to the apparatus in which it is burned—that is, combustible gas which has not been heated after leaving the apparatus in

which it was produced and prior to its introduction into the apparatus in which it is burned.

The tendency of modern blast-furnace engineering is to reduce the temperature of the waste gases from the blast-furnace as low as possible, and is a result of the widening of the blast-furnace throat, as now done in the more modern blast-furnaces, in order to save fuel and improve the working of the furnace. In fact, one very high authority says the temperature of the waste gases of a blast-furnace should not exceed 212° Fahrenheit; hence the necessity of having a means of heating the gas so as to be able to command an intensely-heated blast.

The invention consists in the regenerative hot-blast oven having cold blast or air and cold-gas and chimney connections at the cool or chimney end, and having at the hot or combustion-chamber end hot-blast and hot-gas delivery connections, as well as the hot and cold gas and hot and cold air connections for supplying the necessary hot or cold gas to heat the oven by being burned therein by hot or cold air or by a mixture of hot or cold air, and whose walls are so constructed as to provide for expansion and contraction of the several walls, and whose roof is constructed as shown.

It also consists in the horizontal flues and the several connecting pipes and flues or distributing-mains at the cool end, whereby the gas or blast to be heated is equally distributed, and of the flues and pipes and mains at the hot end, whereby the combustible gas to be burned therein is equally distributed.

It also consists in the combustion-chamber divided into single or double compartments by longitudinal walls extending from the roof and to or near the bottom, and having the air blocks or cylinders extending through the casing and into the wall separating the combustion-chamber and regenerator.

It also consists in the combination of the pipes and valves by which hot air is supplied for combustion in the ovens or gas heaters independent of the hot-blast main.

It further consists in the combination of one or more of the above described ovens, used either as blast-ovens or gas-heaters, with one or more ordinary regenerative or above-described ovens used as blast-ovens.

It further consists in the combination of two or more combined ovens and gas-heaters, which are used successively for heating the blast and for heating the combustible gas.

It further consists in the combination, with two or more ordinary regenerative hot-blast ovens, of the necessary hot and cold gas mains, and connections by which they may be used as blast-ovens and gas-heaters, either successively or in couples, all essentially as hereinafter more particularly described.

The combined oven and gas heater is constructed of ordinary fire-brick or of similarly-shaped blocks of fire-brick or other refractory materials, and whose dimensions vary with the temperature of the blast desired, so that all of

the material in the bricks or blocks may be useful in storing up and giving out heat, for with different temperatures the depth to which the effective heat penetrates and is given off varies. It is rectangular in form and is supported by curved segmental walls A of common or red brick, sand, slag, &c., and incased in sheet-iron; or it may be made without the supporting-walls A, with a rectangular casing of sheet-iron properly supported by outside girders or bracing; or the sheets may be put on horizontally in strips whose length is equal to the width of the several sides of the oven, and with their edges upturned flange-like and fastened, thus providing for lateral pressure. It is divided into two parts—B, the regenerator and C, the combustion-chamber—by the wall D, which extends from the bottom to near the top, but allowing space for the horizontal flues S' and from side to side. It is also divided into several independent compartments, either double or single, by means of the roof-supporting walls E, which extend from front to rear and from the roof to the bottom, except the regenerator part of those in the middle of the double compartments, which rest on arches forming the horizontal flues G, and in the combustion-chamber in which those forming the double compartments extend, either as in Fig. 7 to below the connection I, or, as in Fig. 8, they extend to the top of the horizontal flue O. They may extend, as in Fig. 7, to the bottom, in which case each compartment would have a passage, as at I', for removing the dust. The walls E in the middle of the double compartments may extend to between the air-blocks or cylinders H, and the connection I for passage of blast and gas, as in Fig. 7, or they may be cut off above the air cylinders or blocks, as in Fig. 7; but in this case the air cylinders or blocks are supported by the walls J, to prevent sagging from the effects of heat. The combustion-chamber may be constructed as in Fig. 8, in which the walls E in the middle of the compartments may be cut off above the air blocks or cylinders. When so modified the compartments may be made single by extending all of the walls E to the top of the flue O, and each compartment is provided with a connection, I. In order that there may more certainly be an equal distribution of the combustible gas and the heated products of combustion, the mouths of the connections I are placed in the middle of each of the compartments, either double or single. The air for combustion is introduced through the perforated blocks or cylinders H, placed either in the middle walls, E, of the compartments, as in Fig. 7, or in the walls which form the sides of the single or double compartments, as in Fig. 8. The air cylinders or blocks H extend through and even with the casing and into the wall D, so that in case of repair they may readily be replaced from the outside of the oven by removing the connecting-pipe J' and connections K'.

The air blocks or cylinders may be made of

fire clay or brick, metal, or other refractory material, and, if necessary, may be cooled by causing a current of air or water to flow through a pipe, K', which may be embedded therein. The air cylinders or blocks H are connected by pipes J', having regulating-valves M, to the pipe K, having valve L. The pipe K connects with the pipe N, communicating with the combustion-chamber C and having valve O', Figs. 1, 3, and 7, which may be made in the form of a check-valve by having a suitable-sized seat-valve so balanced as to be automatic, so as to prevent any back flow of air when the oven is being heated or is heating gas; but when the oven is heating the blast opens automatically to allow the air necessary for combustion in the other ovens to flow into the pipe N, and thence by the pipe A', which connects it to the similar pipes, N, of the other ovens. When the ovens are in the same line, as in Fig. 17, the pipe N extends only beyond pipe K, to meet pipe A', which joins all pipes N; but when the ovens are opposite each other, as in Figs. 15 and 16, then the extension of the pipes N, after connecting by pipes A' to meet the corresponding pipes N of the opposite ovens, is necessary to complete the circuit of the air-passages for the air for combustion independent of the hot-blast main.

If in all of the compartments except that next the cold-blast entrance a blast of steam or vapor be introduced in the connections F', together with the cold air introduced by the cold-blast connection H', then in all of the compartments there will be a mixed blast, excepting the first, in which it will be of pure atmospheric air, and this will, by the connection N, be furnished for combustion, while a mixed hot blast will be supplied to the furnace. The pipe N is also connected to the cold-air main O² by the pipe Q², having valve P², by which means cold air may be supplied for combustion.

The dust may be removed from the combustion-chamber through the openings I', which may also be used for firing the gas. The dust in the regenerator is removed through the openings A².

The several compartments of the combustion-chamber are also provided with the connections I to the distributing-main O, connected to the dividing-pipes P, which enter the main O midway between the connections I, so as to equally distribute the combustible gas burned in the oven.

The main O may be formed like main G', outside of the oven, as in Figs. 1, 2, and 5, when the connections I will be horizontal; or the main O may be formed in the bottom of the combustion-chamber by arching it over, as in Figs. 3, 4, 8, and 14, and making the vertical connections I to the several compartments.

The outside connections will be by the dividing-pipe P entering the oven and main O, thus formed midway between the connections I. The pipes P are connected to the opposite oven by the pipe Q, having valve C', either directly or by means of similar dividing-pipes

and distributing main, as illustrated in Figs. 15 and 16. The pipe Q is connected to the hot-blast main B', Figs. 5 and 6, by means of the vertical pipe R, valve S, and branches T. The opposite oven is connected similarly to the hot-blast main B' by the connection F.

In the case of a plant of four ovens connected directly with opposite ones, thus forming two couples, as in Figs. 15 and 16, in each of which one oven is used as a gas-heater, while the other is used as a blast-oven, the pipe Q connecting each couple is connected with the corresponding pipe Q of the other couple by the pipe P', in free communication therewith, having valves Q', by means of which hot gas may be supplied from one oven used as a gas-heater to the other used as a gas-heater by opening the valves Q', to pass the proper quantity of gas, and then leaving them open. The pipe Q is also connected to the source of cold-gas supply by the valve W' and main W, by means of which cold gas may be supplied to the ovens or gas-heaters for combustion.

The main W may be used as a hot-gas main by placing a valve, W², in it between the ovens and the source of cold-gas supply, and may be common to the opposite ovens or gas-heaters, as in Fig. 16, and connected to each by connections having valves W'. This construction will admit of three ovens in a plant of four ovens being used, or will give the advantages of having gas-heaters in a plant of three combined ovens and gas-heaters. In case of the three regenerative hot-blast ovens in the apparatus now generally used, they may be altered to my improved system, as in Fig. 17, by adding the necessary hot-air connections for supplying the air necessary for combustion if it is desired to burn the gas by means of a blast of hot air, or the ordinary air-connections may be used, as in Fig. 18, by placing a valve, W², in the cold-gas-supply main W, thus cutting off communication with the furnace or other source of cold gas supply and forming a hot-gas main of the portion thus cut off. The present gas-supply connection thus serves for the passage of the heated gas into and out of the oven, and then add a cold-gas main, W³, and connections L' and valve R' at the cool ends in order to supply the gas to be heated in the apparatus, as in Fig. 18.

The above construction of the main W will allow of the apparatus being extended, as in case of four ovens and gas-heaters, with a minimum cost, by additional ovens to the common main.

The regenerator B is composed of the walls E and D', forming the vertical flues T'. The walls D' extend from the horizontal flues G as high as the wall D, so as to allow sufficient space for the horizontal flue S'. The flues T' are arranged in one set, as in Figs. 5 and 6, so that the products of combustion and gas or blast to be heated pass through the regenerator in but one direction—that is, the former pass down while the latter pass up—thus decreasing the friction. The roof-supporting walls

E extend from the bottom to the roof, except in the double compartments, in which they commence at the top of the arches supporting them.

The flues G are either single or double. In the latter case they are formed by the arches carrying the walls D' and middle walls, E, of the double compartments. In either case they have the connections F' placed in the middle of the compartments for the passage of the blast or gas to be heated, as well as the products of combustion. The connections F' connect with the distributing-main G', having cold-blast connection and valve H', and chimney-connections M', and communicating with the cold-gas-supply main W³ by the dividing-pipes L', having valve R'. The pipes L' are so placed as to be midway between the connections F', which open into the middle of the compartments, so as to equally distribute the gas to be heated. The distributing-main G' and connections F' also serve to equally distribute the blast to be heated. If the flues are arranged as in Fig. 13 then the distributing-main G' may be formed in the lower part of the last set of flues by arching it over and making the main G' thus formed continuous, as in the combustion-chamber, Fig. 8, by removing parts of the walls E and making vertical openings corresponding to the connections F' and opening into the middle of the compartments. The connection of the cold-gas main W³ will then be by the dividing pipes L', having valve R' and entering the oven and main G' thus formed midway between the openings F', which may be made into each compartment separately or may open into two jointly. The chimney and cold-blast communications may then be made directly to the oven and opening into the main G' thus formed, as shown in Fig. 14. The vapor-pipe J², having valve K², has branches L² extending into all of the connections F', excepting the one next the cold-blast connection, Figs. 1, 2, 4, and 5, and into which they discharge the steam or vapor. In case of forming main G' in oven, as in Figs. 13 and 14, then the branches L² open into the compartments above the main G' if it is desired to heat a mixed blast.

The roof is formed of a number of rectangular blocks N'' and wedge-shaped blocks R'' of fire-brick or other refractory material, and whose length equals the distance between the centers of the roof-supporting walls E, upon which they rest. The wedge-shaped blocks are placed in those parts which are removed when access is desired, as shown in Figs. 5 and 6.

The roof-blocks are covered with strips of sheet-iron E', whose width equals the length of the blocks, and having upturned flange-like edges C², which are bolted together and held in place by the girders H², placed transversely upon the flanges and fastened to the outside casing, as shown in Figs. 7, 8, and 9. The strips E' extend only over each portion, either that over the wedge-shaped blocks, and which is removed when access is desired, as in clean-

ing, or over that formed by the rectangular blocks. The strips E' covering the wedge-shaped blocks may slightly overlap the strips E' covering the rectangular blocks, and to 5 which they are bolted, and may, if necessary, be held down by girders; or the strips E' covering the wedge-shaped blocks may meet the strips E' over the rectangular blocks with upturned flange-edges C², as in Figs. 5 and 6, 10 and bolted together. In case access is desired for cleaning the girders, if used, the sheet-iron strips E' and wedge-shaped blocks under them only need be removed.

The several walls of the oven and gas heater 15 are constructed of ordinary fire-brick or similar rectangular-shaped blocks of fire-brick or other refractory materials, whose dimensions vary with the temperature of the blast desired and the temperature to which they are exposed, so that in case of the hotter blast they 20 may be made larger as the depth to which the effective heat is absorbed and subsequently given out increases with the temperature. The bricks or blocks are laid diagonally in reverse 25 directions in the adjacent walls or courses in the same horizontal planes and in the adjacent courses in the same vertical planes, as shown in Figs. 10, 11, and 12, and they are laid on edge or flat, as above described. The walls 30 may also be made by having the bricks or blocks placed on end and overlapping diagonally to different distances.

The bond is formed by having a horizontal bonding-brick, B², extending from one wall to 35 the other, and which is itself held in place and bonded by the vertical bonding-bricks D², placed at each side and alternate ends of the horizontal bonding-bricks B². The bonding-bricks D² extend from the middle of one horizontal bonding-brick, B², across the next and to the middle of the third, and, in addition, the bonding-bricks D² break joints, as in Fig. 10. The bonding-bricks D² may also be placed horizontally, as shown in Fig. 11. The walls may 40 also be bonded horizontally by a bond-brick, E², extending from the middle of one wall to the middle of the bond-brick B², as in Fig. 10.

The walls may be made by laying the bricks flat and diagonally and in reverse directions, 45 as shown in Fig. 12, and bonded by a single bond-brick, F², and by a part of a brick, I², and a whole brick, G², extending into the side wall, as shown. The next bond formed in this manner—by a whole brick, G², and part I²— 50 is so arranged that the whole brick G² shall extend into the other wall, as shown in Fig. 12. This construction of the walls E and D' is continued until they reach the top of the flues T', when the walls E are constructed by laying 55 the bricks diagonally and in reverse courses, as the walls D' were constructed, as shown in Fig. 11, until they reach their proper height.

By having the bricks laid diagonally and in reverse courses and bonded in manner shown, 60 the effects of expansion and contraction are effectually provided against, which is a matter of the greatest importance in regenerative hot-

blast ovens. In some cases this is provided for by saving a space between the brick-work of the oven and the casing; in others by having walls with loose sliding bricks both between the walls and the casing. In all these cases the expansion sought to be provided for is due to the summation of the expansions of all the abutting bricks in the several walls as 7 ordinarily constructed, and which resultant is transferred to the casing to there be met; whereas in my arrangement each brick is free to expand harmlessly into the flues and not to add its linear expansion to that of the others in the 8 same course, as when they abut as in ordinary wall, and so transfer the whole expansion to the outside casing. The lateral expansion of the bricks is harmless and only has a tendency to turn the bricks to a greater angle with the 8⁵ wall. Those forming the bond, as B², expand by pressing diagonally the ones against which they abut, or if the walls are laid as shown in lower part of Fig. 11, in which two bonding-bricks, B², are used, then the expansion is perfectly free. By constructing the walls thus the expansion is provided for as it is produced in each separate brick, while in the old or ordinary method of constructing the walls, in which the bricks abut, the resultant of all the 90 expansions is transferred to the outside casing, which must be very heavy in order to counteract it. In addition to providing for expansion and contraction, the strength of the walls is very greatly increased, so that they can be 95 made much thinner without fear of buckling, and at the same time the efficiency of the material is greatly increased, owing to the fact that the bricks composing the walls extend through the walls from flue to flue and are not 100 shut off by a coating of mortar, which in practice is found to be a much poorer conductor of heat than the fire-brick. Even a thin coating like a wash prevents to a marked degree the passage of heat.

A wall constructed as shown has a greater power of conducting heat into or out of the wall than when the wall is made of several courses of brick each parallel to the direction of the wall, for in the case of a fourteen-inch wall those bricks that are surrounded by mortar are practically of but little, if any, benefit either in storing up or giving out heat. This defect is avoided by the construction as shown in Figs. 10, 11, and 12.

The various valves used in the apparatus may be of any suitable construction.

Methods of working: When using the combined blast-oven and gas-heater as a gas-heater, supposing all valves closed, proceed as follows in 115 order to heat it: Open the chimney-valve M'; then admit air for combustion by opening the valve L and the regulating-valves M, which remain open after having been properly set; then open valve W' to admit cold gas, when the main W is used as a cold-gas main, or hot gas when the main W is used as a hot-gas main by closing the valve W² when the apparatus is 120 arranged in couples, as before described; then

the hot combustible gas may be admitted to one gas-heater from the other through the pipe P' by opening the valves Q' to the proper extent and leaving them open. Now, after the apparatus has become sufficiently heated, in order to heat the combustible gas proceed as follows: Close the air-supply valve L ; then close the gas-supply valve W' , if cold combustible gas is admitted, but if the main W is used as a hot-gas main then valve W' remains open or is opened more fully to allow the heated gas to pass into the main W used as a hot-gas main; then close the chimney-valve M' and open the cold-gas-supply valve R' to admit cold gas from the main W^2 ; then, if the hot gas passes directly to the opposite blast-oven, open the hot-gas valve C' . The valves Q' remain open so as to pass the hot gas from one oven used as a gas-heater to the other used for the same purpose, thus furnishing a supply of highly-heated combustible gas. Then, after the gas-heater has parted with its effective heat it is reversed and again heated when used in couples as follows: Close the hot-gas valve C' and the cold-gas valve R' and open the chimney-valve M' and air-supply valve L . The hot gas to be burned is admitted through the valves Q' , which remain open. If cold gas is burned then it is admitted from the main W by the valve W' .

5 In case the main W is used as a hot-gas main, then the valve W' remains open or is only partially closed.

When the combined oven and gas-heater is used as a blast-oven, in order to heat the oven, all valves being closed, proceed as follows: Open the chimney-valve M' ; then open the hot-gas valve C' , if the gas is supplied that way, or if the gas is supplied by the main W , used either as a hot or cold gas-main, then open the valve W' instead of C' ; then open the air-valve L and the regulating-valves M , which, when properly set, remain open, by which means the oven becomes highly heated by burning there in a highly-heated or cold gas with a blast of highly-heated air. After the apparatus has become sufficiently heated it is reversed and a highly-heated blast produced, as follows: Close the gas-supply valve C' or W' , as the case may be; then close the chimney-valve M' and open the cold-air-blast valve H' , and the steam or vapor valve K^2 , if a mixed blast is heated; then open the hot-blast valve S , by which means a blast of highly-heated air or a mixed blast of air and vapor is supplied. The valve L always remains open when the apparatus is used as a blast-oven. Then, after it has parted with its effective heat it is reversed and again heated by closing the hot-blast valve S , then closing the cold-air valve H' , and the valve K^2 , if used, and opening the chimney-valve M' . It may be necessary, owing to the pressure on the valve M' , to open a supplementary valve or a dust-door, opening outwardly to relieve the pressure by allowing the air to escape, or a slide-valve may be substituted for the seat-valve. Then open the gas-supply valve C' or W' , as the case may be.

When one or more above-described combined ovens and gas-heaters are used in combination and directly connected with one or more blast-ovens, thus forming couples, each consisting of a gas-heater and blast-oven, in the reversal of the couples the blast-ovens must be reversed first in the following manner: Supposing that in one couple, A^5 and B^5 , Figs. 15 and 16, the gas-heater A^5 is, as above described, heating the combustible gas which is burned in its blast-oven B^5 , as above described, and that in the other couple, C^5 and D^5 , Figs. 15 and 16, the gas-heater C^5 is being heated while its blast-oven D^5 is heating the blast, as above described, then, after the blast-oven D^5 and gas-heater A^5 , or either of them, has parted with its effective heat, or the other oven B^5 and gas-heater C^5 , or either of them, has become sufficiently heated, the reversal is as follows: Always commencing with the blast-oven B^5 , which is being heated, in which close hot-gas valve C' and the chimney-valve M' and open the cold-blast valve H' and the hot-blast valve S , so that there may always be a hot-blast going to the furnace and a pressure maintained in the pipes N , pipes A' , and pipes K and connections, then reverse the gas-heater C^5 in the other couple, which has been heated, by closing the air-valve L and the chimney-valve M' and open the cold-gas valve R' , so that there may always be a sufficient supply of heated gas; then reverse the other blast-oven D^5 , which has been heating the blast, by closing the hot-blast valve S and the cold-blast valve H' , and opening the chimney-valve M' and hot-gas-supply valve C' and the air-supply valve L , which then remains open while the oven is used as a blast-oven; then reverse the other gas-heater A^5 by closing the cold-gas valve R' and opening the chimney-valve M' and the air-valve L , gas for combustion being admitted by valve W' or Q' , as the case may be, as above described. Then, after a suitable interval, the apparatus is reversed in the same way.

In the case of altering, as in Fig. 18, a plant of the three regenerative hot-blast ovens generally used to my improved system without adding a fourth oven or gas-heater, and working them or three of the above-described combined blast-ovens and gas-heaters, as in Fig. 16, in both cases as blast-ovens and gas-heaters successively, and in both of which cases the heated gas is conveyed from the oven in which it is heated to the oven in which it is burned by means of a common hot-gas main or a portion of the usual cold-gas main, W , cut off for the purpose of being used as a hot-gas main by means of the valve W^2 , as before described, so that at any time cold gas may be used in the usual way, the heated gas is burned by a blast of heated air, as in Fig. 17, or by ordinary methods in other ovens, as in Fig. 18.

This method of working with three ovens is somewhat different from the above-described methods, and is based on the fact that the oven which has heated the blast still contains a

large amount of heat which is not of a sufficiently-high temperature or intensity to heat the blast to the desired degree, but which can heat the combustible gas sufficiently high, owing to the gas having a much less volume and velocity and greater heat-absorbing power than the blast, and is as follows: Supposing all valves closed; then, in the first oven, H^5 , open the cold-blast valve H' ; then the hot-blast valve S ; then in the second oven, I^5 , open the cold-gas-supply valve R' at chimney side of the oven; then open the gas-valve W' at the combustion-chamber; then in the third oven, K^5 , open the chimney-valve M' and the gas-valve W' at the combustion-chamber to admit the gas to be burned; then open the air-valve L , Fig. 17, or the ordinary air-valve L , Fig. 18, to supply air for combustion, by which means this oven K^5 becomes heated; then after a suitable interval the apparatus is reversed as follows: Always commencing with the oven K^5 , which is being heated, in which close the gas-supply valve W' at the combustion-chamber, and the air-valves L supplying air for combustion, then close the chimney-valve M' and open the cold-air-blast valve H' , and then the hot-blast valve S ; then in the other oven, H^5 , through which the blast is passing, close the hot-blast valve S and the cold-blast valve H' , and open the chimney-valve M' , to allow the air in the oven H^5 to pass out through the chimney; then open the gas-valve W' at the combustion-chamber, and after a suitable interval, so as to allow the air in the oven to be drawn into the chimney and the oven to be filled with gas, in order to avoid the danger of an explosion from a mixture of air and gas in the oven and hot-gas main, then close the chimney-valve M' and open the cold-gas valve R' at the chimney side of the oven, thus having gas pass through the oven and into the hot-gas main; then in the other oven, I^5 , through which gas is passing, close the cold-gas valve R' at chimney side of the oven and open the chimney-valve M' and the valves L , to supply the air necessary for combustion, by which means this oven I^5 becomes heated. Then, after the oven K^5 , which is heating the blast, has parted with its effective heat, or the one, I^5 , which is being heated, has become sufficiently heated, the apparatus is reversed in the same manner, always commencing with the oven I^5 , which is being heated, and then the oven K^5 , which is heating the blast, and lastly reverse the oven H^5 , which is heating the gas. Now, after the first reversal, the apparatus is heated with cold gas burned with hot or cold air, depending on the system used while a heated blast is being furnished. After the second reversal the apparatus is heated by the hot gas burned with hot or cold air, depending on the system used, in addition to furnishing a highly-heated blast to the furnace, and so on. After each reversal hotter gas is used with hotter air, and thus after each reversal a hotter temperature is developed.

In changing the oven which is heating the

blast so as to heat the gas, it may be necessary to open a supplementary valve or dust-door opening outward to take the pressure off of the chimney-valve if it is a seat-valve, or a slide-valve may be substituted. It may be found in practice that the opening of the chimney-valve in the reversal of the oven which has been heating the blast is unnecessary. Then the reversal can be made by closing the hot-blast valve and cold-blast valve, opening the gas-valve at the combustion-chamber, and then the cold-gas valve at the chimney side of the oven.

The following method of working may be used instead of those before described: Supposing one oven, H^5 , is heating the blast, the other, I^5 , is being heated, while the third, K^5 , is heating the gas; then, in order to reverse the apparatus, always commence with the oven I^5 , which is being heated, in order to always have blast going to the furnace, and reverse it as follows: Close the gas-supply valve W' connecting with the hot-gas main W , and close the valves supplying the air for combustion and the chimney-valve M' ; then open the cold-blast valve H' and the hot-blast valve S , thus causing a current of air to flow through it and furnishing a highly-heated blast; then in the other oven, H^5 , through which air is passing, close the hot-blast valve S , and then the cold-blast valve H' , and open the chimney-valve M' , to allow the air in the oven to pass out through the chimney; then open the gas-valve W' at the combustion-chamber, and after a suitable interval, so as to allow the air in the oven to be drawn into the chimney and the oven to be filled with gas, in order to avoid the danger of an explosion from the mixture of air and gas in the oven and hot-gas main, then close the chimney-valve M' and open the cold-gas valve R' at the chimney side of the oven, thus having gas pass through the oven and become highly-heated and passed into the hot-gas main; then in the other oven, K^5 , on gas close the cold-gas supply valve R' at the chimney side of the oven and open the chimney-valve M' , and then open the valves supplying the air necessary for combustion, by which means this oven K^5 becomes highly heated. Then, after the oven I^5 , which is heating the blast, has parted with its effective heat, or the one, K^5 , which is being heated, has become sufficiently heated, the apparatus is reversed in the same manner, always commencing with the oven K^5 , which is being heated, then the one, I^5 , which is heating the blast, and lastly reverse the one, H^5 , heating the combustible gas, thus producing a more intensely heated blast after each reversal.

In changing the oven which is on blast to heating gas the same precautions should be taken as in the other methods.

In the case of arranging four or more combined blast-ovens and gas-heaters or four or more ordinary regenerative hot-blast ovens changed into combined blast-ovens and gas-heaters along a common hot-gas main, but not directly connected together forming couples,

as before described, the construction is entirely similar to that shown in Fig. 17 for the first case and in Fig. 18 for the second. In either case any two may be used as blast-ovens while the others are used as gas-heaters, or only three may be used, as before described, while the fourth is held in reserve or may be repairing. The construction, as shown in Fig. 17, in which the gas is burned with heated air, is preferable, for after each reversal hotter gas is burned with hotter air, thus heating the blast-oven and gas-heater to a higher temperature, and after reversal they furnish hotter air and hotter gas, which, when burned, heats the other oven and gas-heater hotter yet, and so on after each reversal a higher temperature is developed, which is only limited by the resistance of the refractory materials. Hence the operator has at his command a blast whose temperature is enabled to perfectly control by properly proportioning the quantity of gas burned and blast to be heated in the apparatus.

I do not wish to be understood as claiming herein anything embraced in my former application for Letters Patent which was filed March 31, 1880.

What I claim is—

1. The regenerative hot-blast oven having at the hot or combustion-chamber side hot-blast and hot-gas connections for the delivery of a highly-heated blast or of highly-heated gas which has been heated by said oven, and at the same side the connections for the supply of the necessary hot or cold combustible gas and hot or cold air for burning it therein to heat the oven, and having at the cool or chimney side the cold air and vapor and gas connections for the supply of cold air and vapor and cold gas, respectively, when being heated by the oven, and also the chimney-connection for the exit of the products of combustion, substantially as described, whereby highly-heated gas or a blast of highly-heated air or a mixture of air and vapor may be furnished.

2. The combination, with a regenerative hot-blast oven or gas-heater, of the cold-gas main W^3 and connections L' and valve R' , the chimney-valve M' , the distributing-main G' and connections I' , cold-blast main O^2 and valve H' , and vapor-pipe J^2 and valve K^2 , and branch L^2 at the cool or chimney side, and at the hot or combustion-chamber side the connections I and distributing-main O , dividing pipes P , pipe Q and valve C' , pipe P' and valve Q' , gas-main W and valves W' and W^2 , pipe R and valve S , branch T and hot-blast main B' , and the pipe K and valve L , and branches J' and valves M , pipes N and valve O' , pipe A' , pipe Q^2 , and valve P^2 , substantially as described, whereby highly-heated gas or a highly-heated blast of air or a mixture of air and vapor may be produced at will, as specified.

3. The combination of one or more combined regenerative hot-blast ovens or gas-heaters for heating the combustible gas prior to its being burned to heat the apparatus with one or more similar combined or ordinary regenerative hot-

blast ovens to heat the blast, whereby a highly-heated blast may be supplied to a metallurgical furnace, as specified.

4. The regenerative hot-blast oven in which the flues in the compartments are arranged in one set, and having walls constructed of ordinary fire-brick or similar-shaped blocks of fire-brick or other refractory materials, whose dimensions vary with the temperature to which they are exposed and of the temperature of the blast desired, and which are laid diagonally and in reverse directions in adjacent courses, whereby the effects of expansion and contraction are effectively provided for and the efficiency of the apparatus greatly increased, substantially as specified.

5. In a regenerative hot-blast oven, the combustion-chamber divided into single or double compartments, each having a gas-supply connection, and air-supply blocks or cylinders placed in the side and partition walls and extending through the casing, whereby a more equal heating of the apparatus and repairs are greatly facilitated, as specified.

6. The combination, with a regenerative hot-blast oven or gas-heater, of the cold-gas main W^3 , pipes L' and valve R' , distributing-main G' , chimney-valve M' , cold-blast main O^2 and valve H' , vapor-pipe J^2 and valve K^2 , and branch L^2 and the connections I' , whereby the gas or blast to be heated are equally distributed and the efficiency of the apparatus greatly increased, as specified.

7. The combination, with a regenerative hot-blast oven or gas-heater, of the distributing-main O and connections I , the dividing pipe P , pipes Q and valves C' , pipe R , valve S , gas-main W and valves W' and W^2 , pipe P' , and valve Q' , whereby the combustible gas to be burned in the oven to heat it is equally distributed and the oven equally heated and the efficiency of the oven greatly increased.

8. In a regenerative hot-blast apparatus, the combination of the combustion-chamber C , the air blocks or cylinder H , pipes J' and valves M , pipe K and valve L , pipe N and valve O , pipe A' , pipe Q^2 and valve P^2 , and cold-blast main O^2 , substantially as described, whereby highly-heated or cold air may be supplied for combustion directly from one oven to the others independently of the hot-blast main, as specified.

9. In a regenerative hot-blast oven, the roof constructed of rectangular and wedge-shaped blocks resting on the longitudinal partition-walls and covered with strips of sheet-iron equal in width to the length of the blocks, and having upturned flanged edges bolted together and held in place by girders placed transversely to the flanges and fastened to the casing, substantially as specified.

In testimony whereof I have hereunto set my hand in the presence of two subscribing witnesses.
